Patented Mar. 26, 1918.

UNITED STATES PATENT OFFICE.

HERMAN G. FISCHER, OF CHICAGO, ILLINOIS, ASSIGNOR OF ONE-HALF TO HUGH A. THOMPSON, OF LEESBURG, VIRGINIA.

VENTILATED SPARK-GAP.

1,260,355.

Specification of Letters Patent. Patented Mar. 26, 1918.

Application filed April 1, 1916. Serial No. 88,327.

To all whom it may concern:

Be it known that I, HERMAN G. FISCHER, a citizen of the United States, residing in Chicago, in the county of Cook and State of Illinois, have invented a new and useful Improvement in Ventilated Spark-Gaps, of which the following is a specification.

This invention relates in general to spark gaps and more particularly to devices of this character used in connection with high potential physicians' electrical equipment. Instruments of this character render necessary the incorporation of a spark gap in the circuit with the condenser. The crackling noise of the sparks at the gap must be muffled in order that the patients being treated may not hear this noise and become nervous and alarmed.

Prior to my invention the sparking device has consisted of a multiple of gaps, each of which is inclosed in a muffler or individual housing, deadening or entirely eliminating the sound. These gaps have, however, been closed to the outside air and it has been found that the amperage of the current has become reduced materially in amount when the apparatus is in continued use, this being due to the change of molecular construction of the air constituents and to the heating of the air particles. My invention contemplates the provision of a muffled multiple spark gap which may be run continuously at an even and readily controlled amperage.

A principal object of this invention is the provision of a multiple spark gap which will be silent, or substantially silent, in operation and which can be relied upon to deliver electrical current of predetermined and uniform characteristics.

Other objects and advantages of the invention will be apparent as it is better understood from the following description when considered in connection with the accompanying drawing illustrating a preferred embodiment thereof.

On the drawing,

Figure 1 is a side elevation of a multiple spark gap embodying my invention, parts being broken away to disclose the internal construction;

Fig. 2 is an end view of the same; and

Fig. 3 is a section taken transversely of the device.

For the purpose of illustrating my in-

vention I have shown on the drawing a 55 multiple spark gap in which my present invention is embodied. On the drawing reference characters 4 represent what may be termed end holding plates which may be of any desired material and which carry 60 three side bars 5, preferably of glass, fitting in sockets 6 appropriately arranged in the end plates 4. The spark gaps indicated at 7 occur between units 8 of any usual material. These units are arranged in alignment and the adjacent ones of two adjacent gaps are connected together by screws 9, the end ones being connected by screws 10 with transverse plates 11 of current conducting material. A similar plate 12 is located upon 70 each screw 9 which connects the adjacent gap elements 8 of adjacent spark gaps. Each gap 7 is inclosed in a two-part housing 13, 18, each part 13 being fastened by an appropriate screw 9 between the element 75 and the adjacent plate 11 or 12. These housing parts 13 may also be of current conducting material. The housing parts are insulated from each other by a mica plate 14 forming a partition in the housing. 80 Each plate 14 is provided with a restricted opening 15 about the spark gap proper. The plates 11 and 12 are recessed at two points at 16 to be engaged by appropriate glass connectors 5 and are of dimension 85 causing them to engage the other glass connector 5 at 17 so that the glass connectors hold them in place. An end clamp 18 presses against each end plate 11 and causes the parts to be pressed tightly together 90 through a screw post 19 in threaded engagement with an appropriate end plate or member 4. All of the plates 11 and 12 are perforated at 21 for engagement by a connecting rod 22 having an insulated handle 23, this handle permitting the rod to be pulled in and out to govern the number of spark gaps actually in operation, it being shown in Fig. 1 as having them all inoperative by reason of the passage of current 100 through the rod 22 instead of across the gaps. So much of the multiple spark gap described has been tested and employed prior to my invention and it has been air confined in the housings formed by the 105 housing parts 13, 18 that has in the past interfered with the prolonged efficient operation of the device. In accordance with my

invention I provide communicating apertures or openings 24 between succeeding housings and stagger these successive apertures with respect to each other. I also 5 provide an opening 25 through the screw posts 19 which, in the present instance, constitute the binding posts with which the wires of the circuit may be engaged to include the spark device therein. Air is admitted from the right viewing Fig. 1 and 10 passes along the path defined by the arrows and out at the left. In order that this action may be positive I provide a tube 26 for the introduction of compressed air, causing 15 air to be blown continuously through the tubes when in operation. I have found in the devices in use prior to my invention that the current has dropped within a period of, for example an hour and a half, from 700 20 milliamperes to approximately 200, and that when air has been forced through in the manner described the efficiency has been unimpaired over a run of several hours, no variation in the current being shown. 25 It is thought that the invention and many of its attendant advantages will be understood from the foregoing description, and it will be apparent that various changes 30 may be made in the form, construction and arrangement of the parts without departing from the spirit and scope of the invention or sacrificing any of its material advantages,

the form hereinbefore described being merely a preferred embodiment thereof.

I claim:—

1. In an apparatus of the character described the combination of a plurality of connected spark gaps, and individual housings for the same for the purpose of reducing the sound of said sparks, said housings 40 having communicating openings to permit the passage of air.

2. In an apparatus of the character described the combination of a plurality of connected spark gaps, individual housings 45 for the same, said housings having communicating openings staggered with relation to each other for permitting air to pass through said housings in a circuitous path.

3. In an apparatus of the character described the combination of a spark gap, a housing for the same, a partition in said housing having a restricted aperture through which the spark may pass, and means for forcing air through said housing 50 and through said aperture across the gap.

In testimony whereof, I have hereunto set my hand in the presence of two subscribing witnesses.

HERMAN G. FISCHER.
